US0D1006996S

(12) **United States Design Patent** (10) **Patent No.:** **US D1,006,996 S**
(45) **Date of Patent:** **** Dec. 5, 2023**

(54) **PHOTOTHERAPY LAMP**

(71) Applicant: **SHENZHEN JIYIN TECHNOLOGY CO., LTD.**, Shenzhen (CN)

(72) Inventor: **Qiuyan Lin**, Shenzhen (CN)

(**) Term: **15 Years**

(21) Appl. No.: **29/828,213**

(22) Filed: **Feb. 24, 2022**

(51) **LOC (14) Cl. 24-01**

(52) **U.S. Cl.**

USPC **D24/210**

(58) **Field of Classification Search**

USPC ..... D24/107, 133, 188, 200, 206, 209, 210, D24/211, 214, 215, 231; D26/37, 39, 67, D26/68, 69, 74, 76, 80, 93, 104, 106, D26/110, 120; D2/865, 866; D28/10, 99 CPC A61N 5/062; A61N 5/0616; A61N 5/0618; A61N 2005/0642; A61N 2005/0644; A61N 2005/0645; A61N 2005/0647; A61N 2005/0654; A61N 2005/0659; A61N 2005/066; A61N 5/0611; A61N 2005/0662

(57) **CLAIM**

The ornamental design for a phototherapy lamp, as shown and described.

DESCRIPTION

FIG. 1 is a bottom, front, right perspective view of a photodynamic therapy device, showing my new design;

FIG. 2 is a top, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, rear, left perspective view in condition of use; and,

FIG. 10 is an enlarged view of detail “10” of FIG. 1, for clarity of disclosure.

The equal-length broken lines in the drawings depict portions of the phototherapy device that form no part of the claimed design.

1 Claim, 10 Drawing Sheets
